MACHINE TOOL

Heinrich Naderhoff, Goppingen, Wurttemberg, Germany, assignor to L. Schuler A. G., Goppingen, Wurttemberg, Germany

Application February 12, 1952, Serial No. 271,125

Claims priority, application Germany March 1, 1951

5 Claims. (Cl. 164—50)

This invention relates to machine tools, for example groove punching machines having a work feed means which after an adjustable number of working strokes, is returned to an initial position.

Groove punching machines are known in which the feed means, after insertion of a blank, is moved to an initial position by hand after which the tool movement and the stepwise work feed dependent on said tool movement, are also started by hand, and finally the tool and the work feed are brought to rest after completed work operations.

The present invention, however, consists in providing an electrical control system having a press button starting switch for switching on a power driven fast return travel of the feed means after the insertion of a work blank, in the case of a groove punching machine, a fast return travel of the guide frame for the work blank, and automatic switching off means for the fast return travel when said feed means reaches its end position, automatic switching on means for the tool movement and means dependent on said movement for the stepwise work feed at the end of a work operation. The great manual exertion required for the return movement of the feed means, in the case of groove punching machines, the holder frame, and the manual starting, are all overcome by the electrical control system according to the present invention. The starting now takes place without any physical strain by mere actuation of an electrical hand or pedal switch, whereupon the return travel of the feed means to its initial position and its reversal take place automatically. Machines in accordance with the invention are therefore most suitable for operation by younger and unskilled operators, particularly young persons of lesser physical strength.

According to another feature of the invention, the power drive means for the fast return travel comprises an electric motor, a disc coupling actuated by an electromagnet in dependency on the control system to engage and disengage said motor, and means for operating said electromagnet including a circuit breaker and independent switch-on and switch-off press-button switches. The invention also comprises the inclusion in the system of a circuit breaker actuated by the switch-on press-button switch, said circuit breaker controlling the fast return travel coupling, for example, by means of a transformer feeding the coupling actuating the electromagnet through a rectifier, and a magnetic release means for a locking device adapted to hold the work feed means in its working and end positions, the arrangement being such that the circuit breaker receives operating voltage over a switch dependent on the tool engaging and disengaging movements, which switch is closed when the drive of the tool and of the work feed means is disengaged.

Further features will be apparent from the following description in conjunction with the claims and the drawing which illustrates diagrammatically the control system according to the present invention.

In the system illustrated there is connected to a three-

2

phase network RST, through fuses 5, an electric motor 1 for the drive of a fast return gear. The motor can be switched on and off by means of a circuit breaker 2 in the circuit of which are arranged two push button switches 3 and 4 which are independent of each other and from the other control means hereinafter described. The press button switch 3 serves for switching on and the switch 4 for switching off the motor 1.

The motor drives, through an electromagnetically operated plate clutch 6, a shaft 37 and a pinion 38, the diagrammatically indicated work carrier 7 of the machine and guides it back into the starting position shown in broken lines. For the purpose of operating the clutch 6, there are a push-button switch 9, an engaging relay 8, a transformer 10, and a rectifier 11. An electromagnet 12, which is switched on when the relay is closed, is also connected to the engaging relay 8. The armature of this magnet is in operative connection, through a rod system (not shown), with a rod 20 in such manner that when the magnet 12 is switched on the rod 20 moves in the direction of the arrow 20'. The rod 20 is so connected, through a locking rod system consisting of a two-armed lever 31, 32 rockably mounted about a pivot 30, a two-armed lever 34, 35 rockably mounted about a pivot 33, and a rod 36 pivotally connected to the arms 32 and 34, to a member 42 which locks the feed device in the advanced position, that when the magnet 12 is switched on the locking is cancelled.

A limit switch 13 is provided at the end of the return travel of the feed means, which switch 13 is connected to the circuit breaker 8 and also to a magnet 14 controlling the tool movement and the work feed movement. This magnet 14 is operatively connected to a rod which transmits the movement to operate a second switch-off magnet 17. To the rod there are connected two switches 15 and 18 in such a manner that the switch 15 when the rod is in disengaged position is in the switch-on position and at the same time the switch 18 is held in switch-off position, whereas when the rod is in engaged position the switch 15 is held in switch-off position and the switch 18 in switch-on position. The switch 15 lies in front of the switch-on circuit breaker. The switch 18 is in the circuit of the disengaging magnet 17, behind a limit switch 16 arranged at the end of the forward stroke 35 of the feed means, and in parallel with two series-arranged switches 19 and 21. The rod 20 actuated by the magnet 12 is pivotally connected to an arm 24 of a three-armed lever 24, 25 and 26 pivoted at 28. The three-armed lever receives an oscillating movement from a cam 22 which makes one rotation with the shaft 29 during the punching of each groove. The arm 26 of the three-armed lever carries a roller 27 engaging the periphery of the cam 22. This cam 22 is also provided in one side face with a cam groove 23 controlling a switch 21 in such a manner that the switch is held closed during the angle of rotation determined by the groove 23. The rod 20 in operative connection with the magnet 12 also acts on the arm 24 of the three-armed lever 24, 25 and 26, which is mounted to rock about pivot 28. The arm 26 of the three-armed lever bears through the roller 27 against the periphery of the cam disc 22, which turns once with the crankshaft driving the ram 39 during the stamping-out of a slot and imparts a pendulum movement to the three-armed lever 24, 25 and 26. On the crankshaft 29 a crankdisc 40 is fastened, by which a pawl ratchet mechanism 41 is driven for the stepwise advance of the guide frame 7.

The operation of the said system is as follows:

In the illustrated position of the parts, the work feed means is in its foremost position in which the guide frame 7 of the feed means holds the limit switch 16 closed. The rod for actuating the work feed and the tool move-

ment is in disengaged position, so that upon the closing of the switch 15 the circuit breaker 8 is pre-set for actuation. Before the switch-on switch 9 is closed, the motor 1 is switched on by the press button 3 over the circuit breaker 2, which is shown in switch-off position. The motor movement is at first not transmitted further because the disc coupling 6 is open. By closing the switch 9 the electromagnet which energizes the disc coupling over the circuit breaker 8 is actuated. The motor is thereby coupled to the machine so that the guide frame 7 is driven and moves at fast speed into the broken line position, after locking of the guide frame has been released by the magnet 12 energized over the circuit breaker 8. At the beginning of the fast return stroke, the switch 16 opens under the action of a spring, not shown. At the end of the fast return stroke, the frame 7 actuates the limit switch 13 whereby the circuit breaker 8 is de-energized and returns into its switch-off position so that the coupling 6 is again de-energized. The limit switch 13 also energizes the engaging magnet 14 so that now the stepwise operating work feed and tool movement are initiated. At the beginning of the work stroke the switch 13, for example by the action of a spring not shown, returns to the illustrated position in which the closing of the circuit breaker 8 again becomes possible. When such closing takes place, the switch 15 is opened, and the switch 18 closed. The closing of the switch 18 prepares for the actuation of the disengaging magnet 17. This takes place when the frame 7 at the end of its work stroke again closes the limit switch 16, or when the switch 21 in parallel with the switch 16 is closed by the action of the cam groove 23, as long as the rod 20 occupies a position in which the switch 19 also is closed. This is the case when the locking means for the feed means, which is actuated by the rod 20 and, for example, may consist of a holder pin, has not arrived in the locking position. The cam groove 23 holds the switch 21 closed for a time corresponding to the period of locking; on unlocking, the rod 20 is shifted in the direction of the arrow 20', the arm 25 is thus raised so that the switch 19 is closed and closure of switch 21 by means of the magnet 17 produces disengagement. In the illustrated position the parts are shown with the feed means locked. During the unlocking movement the cam groove 23 releases the switch 21 so that it opens and thus prevents the energizing of the magnet 17 by closing the switch 19, notwithstanding that the feed means is not locked, while this means advances the blank one step. At the end of this punch feed, the cam disc 22 is again in the angular position which permits the retraction of the rod 20 and simultaneous engagement of the locking means. Should the locking means fail to operate so that the rod 20 does not return, then the switch 19 would still be closed and the switch 21 would be closed by the cam groove 23, and thereby the disengaging magnet 17 energized. The parts 19 and 21 to 28 thus constitute a safety device preventing operation of the punching when the feed means is not locked.

The magnet 17 when it is energized by the limit switch 16 or over the safety switch 19, disengages the feed means and the tool movement. If the disengaging magnet is energized by the limit switch 16, then the parts, after the disengagement, are returned to the illustrated position, except for the still running motor 1. After insertion of a new blank in the guide frame, closing the switch 9 will initiate a new work operation in the manner hereinbefore described.

I claim:

1. An electrical control arrangement for a slotting or the like machine of the kind in which a work carrier or feed mechanism therefor is moved back to a starting position after the completion of a pre-determined number of intermittent slotting or punching work operations, comprising a push button switch for switching-on a power driven high speed return of the work carrier or feed

mechanism after insertion of a blank workpiece, and means operative for automatically switching-on the high speed return and then switching-off the high speed return on reaching the end position, automatically switching-on the drive for a tool and, dependently thereon, the intermittent working feed.

2. An electrical control arrangement according to claim 1, wherein an electric motor is provided for the power drive for the high speed return and adapted to be coupled and uncoupled through a plate clutch operated electromagnetically in dependence on the control arrangement, said motor being adapted to be switched on and off through a relay operated by independent switching-on and switching-off buttons.

3. An electrical control arrangement according to claim 1, wherein an electric motor is provided for the power drive for the high speed return and adapted to be coupled and uncoupled through a plate clutch operated electromagnetically in dependence on the control arrangement, said motor being adapted to be switched on and off through a relay operated by independent switching-on and switching-off buttons, and in which a switch relay is provided operated by the engaging switch and by means of which the high speed return clutch is controlled feeding the clutch magnet with the aid of a rectifier, and in which a magnetic release device is provided for a locking means holding the feed device in the working and end positions, while the working voltage is supplied to the switch relay through a switch dependent on the engagement and disengagement of the tool, said last-mentioned switch being closed when the drive of the tool and of the working feed is disconnected.

4. An electrical control arrangement according to claim 1, wherein an electric motor is provided for the power drive for the high speed return and adapted to be coupled and uncoupled through a plate clutch operated electromagnetically in dependence on the control arrangement, said motor being adapted to be switched on and off through a relay operated by independent switching-on and switching-off buttons, and in which a switch relay is provided operated by the engaging switch and by means of which the high speed return clutch is controlled feeding the clutch magnet with the aid of a rectifier, and in which a magnetic release device is provided for a locking means holding the feed device in the working and end positions, while the working voltage is supplied to the switch relay through a switch dependent on the engagement and disengagement of the tool, said last-mentioned switch being closed when the drive of the tool and of the working feed is disconnected and a second switch provided dependent on the engagement and disengagement of the tool including the switch by which the engaging relay is connected to voltage when disengagement occurs, said additional switch being closed in the engaged position and is in the circuit of a disconnecting magnet so that the latter becomes operative as soon as further switches in the same circuit are closed including a switch automatically closed by the feed device at the end of the work cycle.

5. An electrical control arrangement according to claim 1, wherein an electric motor is provided for the power drive for the high speed return and adapted to be coupled and uncoupled through a plate clutch operated electromagnetically in dependence on the control arrangement, said motor being adapted to be switched on and off through a relay operated by independent switching-on and switching-off buttons, and in which a switch relay is provided operated by the engaging switch and by means of which the high speed return clutch is controlled feeding the clutch magnet with the aid of a rectifier, and in which a magnetic release device is provided for a locking means holding the feed device in the working and end positions, while the working voltage is supplied to the switch relay through a switch dependent on the engagement and disengagement of the tool, said last-mentioned

switch being closed when the drive of the tool and of the working feed is disconnected, and a switch operated by the feed device at the end of the high speed return of the latter provided for a magnet effecting the engagement of the tool and working feed drive and at the same time 5 releases the engaging relay.
